(57) **CLAIM**

We claim the ornamental design for a medical therapy device for the stimulation of human tissue, as shown and described.

DESCRIPTION

FIG. 1 is a perspective view of a medical therapy device comprising a new, original and ornamental design;

FIG. 2 is another perspective view of the medical therapy device rotated 90° from the position shown in FIG. 1;
FIG. 3 is a bottom view of the medical therapy device shown in FIG. 1;

FIG. 4 is a top plan view of the medical therapy device shown in FIG. 1;

FIG. 5 is a rear elevational view of the medical therapy device shown in FIG. 1;

FIG. 6 is a front elevational view of the medical therapy device shown in FIG. 1;

FIG. 7 is a right side elevational view of the medical therapy device shown in FIG. 1;

FIG. 8 is a left side elevational view of the medical therapy device shown in FIG. 1;

FIG. 9 is an exploded view of the medical therapy device shown in FIG. 1;

FIG. 10 is a perspective view of a pod that forms part of the medical therapy device shown in FIG. 1;

FIG. 11 is a bottom view of the pod of the medical therapy device shown in FIG. 10;

FIG. 12 is a top plan view of the pod of the medical therapy device shown in FIG. 10;

FIG. 13 is a rear elevational view of the pod of the medical therapy device shown in FIG. 10;

FIG. 14 is a front elevational view of the pod of the medical therapy device shown in FIG. 10;

FIG. 15 is a right side elevational view of the pod of the medical therapy device shown in FIG. 10;

FIG. 16 is a left side elevational view of the pod of the medical therapy device shown in FIG. 10;

FIG. 17 is a perspective view of a consumable that forms part of the medical therapy device shown in FIG. 1;

FIG. 18 is bottom plan view of the consumable of the medical therapy device shown in FIG. 17;

FIG. 19 is a top plan view of the consumable of the medical therapy device shown in FIG. 17;

FIG. 20 is a rear elevational view of the consumable of the medical therapy device shown in FIG. 17;

FIG. 21 is a front elevational view of the consumable of the medical therapy device shown in FIG. 17;

FIG. 22 is a right side elevational view of the consumable of the medical therapy device shown in FIG. 17; and,

FIG. 23 is a left side elevational view of the consumable of the medical therapy device shown in FIG. 17.
